DESIGN FOR A WHEEL OR TIRE CHANGE REST OR SIMILAR ARTICLE

Lloyd E. Bryson, Los Angeles, Calif.

Application April 28, 1945, Serial No. 119,292

Term of patent 14 years

(Cl. D41—1)

To all whom it may concern:

Be it known that I, Lloyd E. Bryson, a citizen of the United States, residing in Los Angeles, in the county of Los Angeles, State of California, have invented a new, original, and ornamental Design for a Wheel or Tire Change Rest or Similar Article, of which the following is a specification, reference being had to the accompanying drawing, forming a part thereof.

Figure 1 is a top plan view of a wheel or tire change rest embodying my novel design.

Figure 2 is a bottom plan view of the same.

Figure 3 is a side elevational view of the same.

Figure 4 is an end elevational view of the same.

I claim:

The ornamental design for a wheel or tire change rest or similar article, as shown.

LLOYD E. BRYSON.
